Primary Examiner — Thomas Johannes*Assistant Examiner* — Gino Colan(74) *Attorney, Agent, or Firm* — Foley & Lardner LLP(57) **CLAIM**

The ornamental design for a pan for wheelbarrows, as shown and described.

DESCRIPTION

FIG. 1 is a perspective view of a pan for wheelbarrows showing my new design;

FIG. 2 is a front view of the pan for wheelbarrows of FIG. 1; FIG. 3 is a rear view of the pan for wheelbarrows of FIG. 1; FIG. 4 is a right side view of the pan for wheelbarrows of FIG. 1;

FIG. 5 is a left side view of the pan for wheelbarrows of FIG. 1;

FIG. 6 is a top view of the pan for wheelbarrows of FIG. 1; and,

FIG. 7 is a bottom view of the pan for wheelbarrows of FIG. 1.

The broken lines in the drawings are for illustrative purposes only and form no part of the claimed design.

1 Claim, 5 Drawing Sheets(56)
